UNITED STATES PATENT OFFICE.

SIDNEY AUGUSTIN ROUSSEAU, OF DE WITT, ARKANSAS.

AIR-BRAKE CONNECTION.

1,264,687.

Specification of Letters Patent. Patented Apr. 30, 1918.

Application filed June 26, 1917. Serial No. 176,988.

To all whom it may concern:

Be it known that I, SIDNEY A. ROUSSEAU, a citizen of the United States, and a resident of De Witt, in the county of Arkansas and 5 State of Arkansas, have invented new and useful Improvements in Air-Brake Connections, of which the following is a specification.

My invention is an improvement in air 10 brake connections, and has for its object to provide mechanism of the character specified, adapted for coupling the train pipe sections of an air brake system without requiring the brakeman to go between the cars, 15 the coupling being automatically brought about by the coupling of the cars, and wherein in the act of coupling connects the sections of the train pipe.

In the drawings:

20 Figure 1 is a side view showing the improved coupler in uncoupled position;

Fig. 2 is a similar view showing the coupler in coupled position;

Fig. 3 is a partial side view of a coupling 25 section, with parts in section;

Fig. 4 is a section on the line 4—4 of Fig. 3, looking in the direction of the arrows adjacent the line;

Fig. 5 is a partial side view showing a 30 modified construction of valve operating mechanism;

Fig. 6 is a sectional view of a modified construction of connection between the train pipe and the coupling head.

35 The present embodiment of the invention is shown in connection with cars 1 and 2, each of which has the usual automatic coupling head 3 for coupling the cars.

The train pipe sections 4 of the cars 1 and 40 2 are connected by means of flexible hose 5 with cylindrical casings 6, which are mounted to slide in brackets 7 supported below the car. Each of these casings 6 has at its outer end a head 6^a, and these heads are adapted 45 to abut, as shown in Fig. 2, to connect the casings. It will be noticed that each casing at the head is reamed or counterbored, as indicated at 8, and a gasket or packing ring 9 of rubber or the like is held in each counterbore, each counterbore having its wall 50 undercut, as shown in Fig. 3, to receive a marginal flange or rib on the gasket to hold the gasket in place.

Each casing has threaded thereon a stop 55 collar 10 intermediate its ends, and a coil spring 11 encircles each casing between the

stop collar and the inner end of the supporting bracket 7, the springs normally acting to force the casings away from the car and toward the adjacent car. 60

The passage of the fluid under pressure through each casing is controlled by a valve 12, and in the embodiment of the invention shown in Figs. 1 to 4, this valve has a handle 13 extending radially therefrom, and between a pair of pins 14 on the bracket 7. The arrangement is such that when the casing is pushed outwardly under the influence of the spring, that is, when the cars are not coupled as shown in Fig. 1, the valve will be 70 turned through the engagement of the handle with the pins into closed position, closing the bore of the casing and shutting off the fluid under pressure. However, when the cars are moved together with the heads 75 6^a abutting and the said heads are forced inwardly as shown in Fig. 2, the pins will cause the arm or handle to move the valve in the opposite direction, to open the valve, to permit the fluid under pressure to pass 80 between the pipe sections. Thus the act of coupling the cars automatically couples the train pipe sections, and opens the valve so that the said sections are in communication 85 with each other.

The gaskets 9, together with the springs 11 which act at all times to force and hold the gaskets together, prevent escape of the air at the joint.

In the embodiment of the invention shown 90 in Fig. 5, the casing 15, which corresponds in all respects to the casings 6, is mounted to slide in a bracket 16 corresponding to the bracket 7. Instead of the arm or handle 13 connected with the valve, however, a pinion 95 17 is secured to the valve 18, and this pinion meshes with a rack bar 19 on the bracket. It will be obvious that when the casing is pushed outwardly under the influence of the spring the valve will be closed, while when 100 the casing is pushed inwardly by the other coupling section the valve will be opened.

In Fig. 6 is shown a modified construction of connection between the train pipe and the coupling head, wherein the flexible hose 105 is omitted. In this construction it will be noticed that a sectional connection is provided, consisting of an outer section 20 and an inner section 21 mounted to slide in the outer section. In fact, the pipe is a telescoping pipe, and a gasket 22 is arranged 110 between the sections for forming a seal.

I claim:

A coupling for train pipe sections, comprising a casing having at one end a head adapted to abut the head of the other casing and having a gasket for engaging the gasket of the other head to seal the joint, a bracket adapted for connection with the car in which the casing is mounted to slide, each casing being adapted for connection with the train pipe of the car at its inner end, a stop collar adjustably mounted on each cas-

ing, a spring between the collar and the bracket and normally forcing the casing away from the car, a valve controlling the flow of pressure through the casing, and means controlled by the movement of the casing under the influence of the spring and under the pressure of the other coupling section for controlling the valve to close and open the casing. 15

SIDNEY AUGUSTIN ROUSSEAU.
